Primary Examiner — Marissa J Cash*Assistant Examiner* — Altaira J Swangin(74) *Attorney, Agent, or Firm* — Nixon & Vanderhye(57) **CLAIM**

The ornamental design for an electronic device, as shown and described.

DESCRIPTION

FIG. 1 is a front, left side and top perspective view of an electronic device showing the new design;

FIG. 2 is a rear, left side, and top perspective view thereof;

FIG. 3 is a rear, right side, and bottom perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines shown in the drawings illustrate portions of the electronic device that form no part of the claimed design.

1 Claim, 7 Drawing Sheets(56)
